UNITED STATES PATENT OFFICE.

JOHN J. COMER, OF CHICAGO, ILLINOIS, ASSIGNOR TO AUTOMATIC ENUNCIATOR COMPANY, OF CHICAGO, ILLINOIS, A CORPORATION OF ILLINOIS.

DIFFERENTIAL MICROPHONE-TRANSMITTER.

1,033,087.

Specification of Letters Patent. Patented July 23, 1912.

Application filed October 24, 1910. Serial No. 588,789.

To all whom it may concern:

Be it known that I, JOHN J. COMER, a citizen of the United States of America, and resident of Chicago, Cook county, Illinois, have invented a certain new and useful Improvement in Differential Microphone-Transmitters, of which the following is a specification.

My invention relates to transmitters of the kind ordinarily known as differential transmitters.

In the simple form of transmitter of this kind the resistance is varied only at one point in the circuit, or at one point in each circuit, as the case may be, as by the use of a single electrode between two other electrodes. There is, however, a more complex form of differential transmitter in which the resistance is varied at a plurality of points in the circuit, or in each circuit, and in which a plurality of stationary electrodes alternate with a plurality of movable electrodes. It is to this form of differential transmitter that my invention more particularly relates.

Generally stated, the object of my invention is, therefore, to provide an improved and highly efficient differential transmitter of that kind in which a plurality of electrodes are disposed between and alternately with a plurality of other electrodes.

A special object is to provide a transmitter of this type in which the construction is more simple and free from certain complications than those heretofore employed or proposed of similar character.

Another object is to provide an improved construction and arrangement whereby a plurality of stationary electrodes are disposed between and alternately with a plurality of movable electrodes, which movable electrodes are carried on the diaphragm of the transmitter, and whereby the granular carbon between said electrodes receive the benefit of the agitation or shaking produced by the vibration of the diaphragms.

To these and other useful ends, my invention consists in matters hereinafter more fully set forth and claimed.

In the accompanying drawings:—Figure 1 is a longitudinal section of a transmitter embodying the principles of my invention. Fig. 2 is a rear view of the microphone and the disk to which the said microphone is connected by a bridge. Fig. 3 is a sectional

view of the different parts separated. Figs. 4, 5 and 6 are views similar to those previously described, showing a slightly different form of my invention.

As thus illustrated, and referring to Figs. 1 to 3, inclusive, my invention comprises a front plate A provided with a shoulder a on the inside thereof, and with an internal screw threaded portion a'. It is also provided with a central opening a² for the usual mouth piece B. The diaphragm C is seated against the shoulder a, but insulated therefrom, as shown, and is clamped in place by a disk D and a threaded clamping ring E that engages the threaded portion a' of the front plate, the said disk and ring being insulated from each other, and the disk being insulated from the front plate, but not from the diaphragm, the latter being in electrical contact therewith. This disk D has a central aperture d for the microphone F which is carried directly on the back of the diaphragm. Another microphone G is secured to the front of the said diaphragm. The microphone F consists of a metal cup f, front and back movable electrodes f' and f'', a stationary or middle electrode f³, and mica insulating pieces f⁴, f⁵ and f⁶, together with the usual filling f⁷ of granular carbon. The said insulation f⁴ insulates the granular carbon from the metal cup f, and the mica f⁵ insulates the electrode f² from the said cup and diaphragm. The parts f², f⁵ and f⁶ are secured together by the hollow rivet f⁸, and a similar rivet f⁹ secures the electrode f' to the back of the diaphragm. The microphone G is similarly constructed and comprises the metal cup g and the front and back electrodes g' and g'', together with the middle or intermediate electrode g³ and the granular carbon filling g⁴. It also comprises the ring insulation g⁵ and the flat insulating pieces g⁶ and g⁷. The front electrode g' and the insulations g⁶ and g⁷ are clamped to the end wall of the cup g by the hollow rivet g⁸. The two cups f and g have their open ends clamped upon opposite sides of the diaphragm by the rivets g⁹. The electrodes f³ and g³ are electrically secured to the stem H, which extends through the rivets f⁸ and f⁹, and which is adjustably secured to the bridge I on the disk D, the said bridge and disk being insulated from each other. One circuit wire goes to the disk D, to connect with the electrodes f' and

105
110

g²; another wire goes to the electrode *f²*, and a third wire goes to the electrode *g'*; but the electrodes *f³* and *g³* are not connected directly with any circuit connections, the 5 granular carbon being the only medium by which current can pass to or from these two stationary electrodes. The circuits may be of any suitable character. Fluffy asbestos is employed for filling the said hollow rivets 10 after the parts have been assembled and the granular carbon introduced through the passages of said rivets.

In Figs. 4 to 6, inclusive, the construction is substantially the same as that previously 15 described. The only difference, in fact, is that in this case the microphone boxes *J* and *K* have their closed ends secured to the diaphragm, and have their open ends closed by the caps *j* and *k*. Otherwise the two transmitters are the same, as each involves two 20 differential microphones, each microphone comprising a pair of movable electrodes and a stationary electrode.

A differential microphone transmitter of 25 this kind is, I find, particularly adapted for use in loud speaking systems using heavy currents and requiring clear enunciation and pure tone. The microphones are so constructed, it will be observed, that they can 30 be operated at the high temperatures which frequently result from the use of heavy currents for loud speaking purposes. The mica insulation protects the structure when the carbon becomes highly heated.

35 What I claim as my invention is:

1. In a transmitter, a diaphragm, a plurality of electrodes movable with said diaphragm, a plurality of stationary electrodes alternating with said movable electrodes, 40 and a receptacle containing granular carbon, which carbon is between said electrodes, said receptacle being movable with said diaphragm.

2. In a transmitter, a diaphragm, a carbon receptacle and a plurality of electrodes movable with said diaphragm, a plurality of stationary electrodes alternating with said movable electrodes, granular carbon contained in said receptacle between said 50 electrodes, and means inside of the transmitter for electrically and mechanically connecting the said stationary electrodes together.

3. In a transmitter, a diaphragm, a differential microphone mounted on the back of 55 said diaphragm, and a second differential microphone mounted on the front of said diaphragm.

4. In a transmitter, a diaphragm, a differential microphone on the back of said diaphragm, a differential microphone on the front of said diaphragm, a support, and a connection from the said support to the inside of said microphones.

5. In a transmitter, a diaphragm, a stationary electrode in front of said diaphragm, a stationary electrode back of said diaphragm, and connected with said first-mentioned electrode, variable resistance means coöperating with said electrodes, a 70 bridge back of said diaphragm, and a connection from said bridge to said stationary electrodes.

6. In a transmitter, a diaphragm, a plurality of electrodes, a filling of granular carbon between said electrodes, and a stem rigidly connecting together a plurality of 75 said electrodes, which stem also serves as an electrical connection between said electrodes.

7. In a transmitter, a diaphragm, a differential microphone on the back of said diaphragm, a differential microphone on the front of said diaphragm, a disk and clamping ring for holding the diaphragm in place, a bridge on the disk, and an adjustable connection from the bridge to said microphones.

8. In a transmitter, a diaphragm, differential microphones disposed on opposite sides of said diaphragm, a support, and a connection from the said support to the said 90 microphones, which connection is an electrical connection between said microphones.

9. In a transmitter, a diaphragm, differential microphones disposed at opposite sides of said diaphragm, and a connection 95 between said microphones extending through said diaphragm, which connection electrically connects one microphone with the other.

Signed by me at Chicago, Illinois, this 100 12th day of October, 1910.

JOHN J. COMER.
